No. 768,242.

PATENTED AUG. 23, 1904.

A. P. SEYMOUR.

ROSETTE.

APPLICATION FILED APR. 27, 1904.

NO MODEL.

UNITED STATES PATENT OFFICE.

ALBERT P. SEYMOUR, OF SYRACUSE, NEW YORK, ASSIGNOR TO PASS & SEYMOUR, INCORPORATED, OF SOLVAY, NEW YORK.

ROSETTE.

SPECIFICATION forming part of Letters Patent No. 768,242, dated August 23, 1904.

Application filed April 27, 1904. Serial No. 205,061. (No model.)

To all whom it may concern:

Be it known that I, ALBERT P. SEYMOUR, a citizen of the United States, residing at Syracuse, in the county of Onondaga and State of New York, have invented certain new and useful Improvements in Rosettes; and I do hereby declare the following to be a full, clear, and exact description of the invention, such as will enable others skilled in the art to which it applies to make and use the same.

This invention relates to an improved means for insulating the wires in so-called "concealed work;" and it consists, essentially, of a rosette having a base or block formed to receive the ends of the two wire tubes, which are arranged better to insulate the wires by protruding from the wall or ceiling, and of a cap entirely covering the block and provided with means for securing it in position.

My invention will be understood by reference to the drawings herewith, in which the same reference letters and numerals of the specification indicate the same parts in all the figures.

Figure I is a vertical cross-section showing the rosette secured in position on the ceiling. Figs. II and III are respectively bottom plan and side elevation of the block. Figs. IV and V are respectively bottom plan and top plan of the cap. Fig. VI is a top plan of the assembled rosette, showing the tubes in section. Fig. VII is a vertical section showing the use of the cap without the block.

In the figures, A indicates the block, formed with the opposite recesses 1 1 sufficiently large to receive the ends of the wire tubes 2 2 of all ordinary sizes. From the tubes the ends of the wires 4 4 are brought through the wire-holes 3 3 adjacent to the wire-terminals 6 6, secured in their seats 9 9 by screws 7 7, having their heads arranged in screw-cavities 8 8, which are preferably filled with insulating-cement. Each terminal carries two binding-screws, respectively, for the wire 4 and the cord. The central reinforcement 11 for strengthening the block is provided with a depression for receiving and holding in position the knot so it cannot drop against the metallic terminals with dan-

ger of cutting the insulation and short-circuiting. The block is secured in position against the ceiling by securing-screws in holes 13 13, having their heads arranged in depressions 14 14, by which they are separated from the terminals. On opposite sides the block is provided with notches 16 16 to engage with columns 17 17 on the inside of the cap B, guiding the arrangement of the parts and provided with screw-holes 15 for the cap-securing screws to hold the cap close up against the ceiling, entirely covering and protecting the block and rendering it unnecessary to glaze the latter. At its inner corner the cap is provided with reinforcing-ribs 20 20, cut away at 21 21 to afford additional space for the wires and cords attached to the terminals. On the lower surface of the cap is the boss 23, formed with an inner cavity 24 and with a cord-hole 25 to receive the knot and to permit the cords to depend.

The important feature of my invention is that it supplies a positive insulation between the wires in the tubes. Heretofore it has been common to arrange the tubes with their ends flush with the ceiling, which does not positively separate the wires projecting from the tubes nor avoid the danger of a short circuit across the plaster.

As shown in Fig. VII the cap in some cases may be used without the block, the tubes being arranged with their ends downwardly extending within the cap, giving a good insulation between the wires, to which the stripped ends of the cords 10 are soldered, the joints taped in the usual way, and the knot in the cords arranged to rest in the cavity and to sustain the weight.

Having thus described my invention, what I claim, and desire to secure by Letters Patent, is—

1. In a rosette for electric wiring, the combination with a block of insulating material having recesses to receive the ends of the insulating-tubes, terminals on the block for the attachment of the wires, and a cap of insulating material to cover the block.

2. In a rosette for electric wiring, the combination with a block of insulating material,

having recesses in its upper surface to receive the ends of insulating-tubes, terminals on the lower surface of the block for the attachment of the wires and cords, means for securing the block in position, a cap of insulating material, entirely to cover the block, and means to secure the cap in position.

3. In a rosette for electric wiring, the combination with a substantially circular, porcelain block having opposite curved recesses in its upper portion to receive the ends of the insulating tubes or conduits, metallic terminals provided with binding-screws arranged on the lower surface of the block adjacent to wire-holes communicating with the respective recesses, screws to secure the block in position, a porcelain cap to cover and surround the block, a boss on the lower surface of the cap, said boss being formed with an internal cavity and a central cord-hole, and screws to secure the cap in position.

4. In a rosette for electric wiring, the combination with a substantially circular, porcelain block having opposite recesses in their upper portions, for receiving the ends of insulating-tubes, wire-holes in the bottoms of said recesses and opposite notches extending from top to bottom of the block margin between the recesses, of two metallic terminals arranged in seats on the lower surface of the block adjacent to the wire-holes, two binding-screws in each terminal for the wire and cord respectively, a central circular reinforcement on the lower surface of the block having a depression, securing-screws for the block having their heads arranged in depressions adjacent to the notches, a porcelain cap, a circular margin on the cap to surround the block, columns in the interior of the cap-margin formed with screw-holes and adapted to fit the

notches, sectional reinforcing-ribs in the inner corner of the cap, a boss on the lower surface of the cap, said boss being formed with an inner cavity and a central knot-hole, and screws to secure the cap in position to cover the block.

5. In a wire-insulating device for concealed work, the combination with the wires suitably arranged in insulating-tubes, of the tubes arranged with their ends extending outwardly from the surface of a wall or ceiling, a cap arranged to cover the ends of the tubes, a boss on the cap provided with an internal cavity and a central cord-hole, and cords having their respective ends connected to the wire ends extending out from the tubes, said cords being knotted and the knot arranged in the cavity, with the cord ends extending downwardly through the cord-hole.

6. In a wire-insulating device for concealed work, the combination with two insulating-tubes arranged with their ends extending downwardly a short distance beyond the surface of the ceiling in which they are supported, of wires arranged in the respective tubes and extending out therefrom, a porcelain cap, having a circular margin and a central cord-hole, screws to secure the cap in position against the ceiling to cover the ends of the tubes, and a pair of cords having their respective ends connected to the wires, said cords being knotted in the interior of the cap and having their ends extending down through the cord-hole.

In testimony whereof I affix my signature in presence of two witnesses.

ALBERT P. SEYMOUR.

Witnesses:

LAMONT STILWELL,
ARTHUR S. VIALL.
